ADJUSTABLE BODY SUPPORT FOR DOG GROOMING

Durward L. Hodges, 210 N. Bagley,
Dallas, Tex. 75211

Filed Aug. 19, 1974, Ser. No. 498,432

Term of patent 14 years

Int. Cl. D30—99

U.S. Cl. D30—40

Fig. 1

Fig. 3

FIG. 1 is a top plan view of an adjustable body support for dog grooming showing my new design;

FIG. 2 is a front elevational view; and

FIG. 3 is a right side elevational view.

I claim:

The ornamental design for an adjustable body support for dog grooming, as shown and described.
